UNITED STATES PATENT OFFICE.

JAMES G. RALPH, OF AURORA, ILLINOIS.

STORM AND SCREEN CONSTRUCTION.

No. 839,640.

Specification of Letters Patent.

Patented Dec. 25, 1906.

Application filed March 14, 1904. Serial No. 198,036.

To all whom it may concern:

Be it known that I, JAMES G. RALPH, of Aurora, in the county of Kane, in the State of Illinois, have invented a certain new and useful Improvement in Storm and Screen Constructors; and I do hereby declare that the following is a full, clear, and exact description thereof, reference being had to the accompanying drawings, in which—

10 Figure 1 is a vertical section of a window provided with storm-sash in accordance with my invention; Fig. 2, an elevation of the outer side of the same; Fig. 3, a detail perspective view of the hanger for the lower sash; 15 Fig. 4, a similar view of the hanger for the upper sash, and Fig. 5 a detail perspective view of the turn-button employed with each sash for fastening the same.

The object of my invention is to provide a 20 construction for windows by which storm-sash and fly-screens can be readily applied, removed, and manipulated which shall be simple and inexpensive in construction; and to this end my invention consists in the construction substantially as hereinafter specified and claimed.

In the drawings, A designates a window-frame of ordinary construction having, as usual, a blind-stop B. Within the frame 30 outside the blind-stop I place my sash, consisting of a lower one C and an upper one D, said sash being shown as glazed, I having selected for the illustration of my invention storm-sash. The top rail of the lower sash and the bottom rail of the upper sash are recessed or rabbeted, so that the two sash have portions that enter the recess of the opposite sash and overlap, and the projecting portion of the rail of the lower sash is at the inner side 40 thereof. On the lower sash, at opposite sides thereof and at or near the upper edge of the sash, are two pins E, that project beyond the sides of the sash, which pins, respectively, are adapted to engage slotted plates F, fastened to the sides of the window-casing, preferably by being let into the same, so that their outer surfaces are flush with the side surfaces of the casing. The slot f of each plate extends inwardly and then downwardly, 45 and the upper wall of the inwardly-extending portion of the slot is projected outward beyond the outer edge of the plate, the purpose of such arrangement being to facilitate the placing of the pin in the slot, for it will be seen that by resting the pin against the side 50 of the plate below the slot and then moving

the sash upward the pin will encounter the projection, and it can then be readily passed inward in the slot and permitted to descend in the downwardly-extending portion thereof. The inner surface of the lug or projection that forms the outer wall of the vertical portion of the slot is inclined downward and inward, so as to act upon the pin to cam or crowd the sash inward against the blind-stop 60 and to make it fit snug and tight. By having the portion of the top rail of the lower sash that overlaps the upper sash on the inner side, as above described, the lower sash can be swung upon the pins, as upon a hinge, outward, as shown in dotted lines in Fig. 1, for purposes of ventilation or otherwise. To hold it when swung outward, a hook or rod G (shown in dotted lines) may be employed pivoted to the lower rail of the shaft and adapted to be caught into an eye H on the windowsill. On the bottom rail of the lower sash I pivot a turn-button I, having oppositely-projecting wings i, whose faces next the sash are inclined, so that when one or the other, 70 whichever happens to be lowermost, engages a pin K in the window-sill; the sash will thereby be drawn tightly inward and securely held in place. The turn-button may be pivoted directly to the sash; but I prefer to pivot 75 it to a plate i', that is secured to the sash by screws that pass through slots i², this arrangement permitting adjusting of the position of the turn-button.

At or near the bottom of the upper sash 80 and at each side thereof is a plate L, that has a hook l to engage a pin M, projecting from the blind-stop, the side of the hook that engages the pin being inclined, so that as the hook moves down over the pin, as it does in 85 placing the sash in position, the sash will be drawn inward against the blind-stop. The plate L is provided with two hooks that extend in opposite directions, the purpose of which is to avoid the construction of this device right and left, for with the two one device answers for either side of the window. For its attachment to the sash the plate L has a laterally-extending flange l', provided with open-ended slots l², through which 90 screws pass. The object in providing the slots is to enable the plate to be adjusted when necessary on account of shrinkage of the wood or for other reasons, so that at all times the parts may be adjusted to secure 95 close fit of the sash. For securing the upper sash at its top a turn-button and pin device 100

110

are employed, precisely as in the case of the lower sash. It will be observed that the devices for securing the lower sash at its upper side and the upper sash at its lower side are 5 at or contiguous to the place where the two sash come together. As a result of this both sash are held tight against the blind-stop at their upper and lower portions, and of course the overlapping of one sash by the other enables one sash to act to hold the other sash 10 against the blind-stop. Nevertheless, both sash are supported so as to be entirely independent of each other, so that either may be swung outward on its pin-support independently of the other. It will be seen that the 15 upper sash can be swung outward merely by releasing its turn-button, and its center of motion being at or near its bottom its top can be made to fit the window-casing very closely.

20 With the upper sash in position the lower sash can be swung out until it is at right angles to the vertical, so that the whole of the window which it incloses can thus be open, and it will be securely held from disengagement from its 25 hangers by the upper sash. The upper sash when in position at all times prevents the lower sash being removed. With both upper and lower storm-sash open ventilation can be had either at top or bottom by opening 30 the inside sash, as may be required.

For the convenient handling of the sash a handle N, which may consist of a simple curved bar, is attached to each side of each sash about half-way from the top to the bottom thereof. In putting the sash in the window the lower sash is preferably put in position first. The sash-hangers and turn-buttons, as will be evident, are applicable to doors, as well as window-sash.

40 Having thus described my invention, what I claim is—

1. In a storm or screen construction, the combination of a sash, hangers therefor consisting of a plate that has a slot that opens 45 outward and thence extends inward and

downward, and a pin for coacting with the slot, the plate having an overhanging or projecting portion at the open end of the slot.

2. In a storm or screen construction, the combination of a window-frame having a 50 projection, such as a blind-stop, a sash on the outside of such projection, and a hinge connection between the sash and frame that permits the sash to be swung outward, that consists of plates having each a slot that opens 55 outward and thence extends inward and downward, and a pin to coact with the slot, said plate having a pin-engaging, overhanging or projecting portion at the open end of the slot.

3. In a storm or screen construction, the combination of two sash therein, one directly above the other, securing means for the upper sash at the bottom thereof on which the sash may swing, securing means for the top 65 of the sash, detachable securing means for the lower sash near the top thereof on which it may swing, the relative position of the lower sash being such that the latter is always retained in position by the upper sash 70 when it is in place, and securing means for the bottom of the lower sash.

4. In a storm or screen construction, the combination of a window-frame, two sash therein, one directly above the other, having 75 overlapping portions, means for securing each of such sash at or near where they come together which permit the sash to swing horizontally independently of each other the upper one opening outward at its top and the 80 lower one opening outward at its bottom, and a projection on the window-frame, such as a blind-stop, against which the sash abut.

In testimony that I claim the foregoing I have hereunto set my hand.

JAMES G. RALPH.
